UNITED STATES PATENT OFFICE.

LEWIS C. SHIPLEY, OF DETROIT, MICHIGAN.

VEHICLE-TOP.

1,136,054.

Specification of Letters Patent. Patented Apr. 20, 1915.

Application filed March 20, 1914. Serial No. 825,985.

To all whom it may concern:

Be it known that I, LEWIS C. SHIPLEY, a citizen of the United States of America, residing at Detroit, in the county of Wayne and State of Michigan, have invented certain new and useful Improvements in Vehicle-Tops, of which the following is a specification, reference being had therein to the accompanying drawings.

- 10 This invention relates to vehicle tops and the objects of my invention are, first, to provide a vehicle top that can be advantageously used in connection with automobiles and easily and quickly collapsed or set up 15 in position; second, to provide a vehicle top embodying novel bows and connections that provide a rigid and durable structure, and third, to accomplish the above results by a mechanical construction that presents a neat 20 appearance, fully protects the occupants of the vehicle without obstructing the view and permits of one person easily manipulating the top when necessary.

With the above and other objects in view, 25 the invention resides in the novel construction, combination and arrangement of parts to be hereinafter fully described and then claimed, and reference will now be had to the drawing, wherein—

- 30 Figure 1 is a longitudinal sectional view of the vehicle top in a set-up position; Fig. 2 is a similar view showing the vehicle top in a collapsed position; Fig. 3 is a longitudinal sectional view upon a smaller scale 35 of a modified form of top in a set-up position; Fig. 4 is a side elevation of the same in a collapsed position, and Fig. 5 is a perspective view of a detached channel member.

- 40 A vehicle top in accordance with this invention comprises a front bow 1 having the ends thereof pivotally connected in the ordinary and well known manner to irons or supports 2, carried by the side of a vehicle 3, adjacent to the rear seat thereof. Pivotally connected to the front bow 1, contiguous to the irons 2, is a rear bow 4 disposed at substantially right angles to the front bow 1 when the top is in a set-up position.

Pivotally connected to the rear side of the front bow 1, as at 5, is an auxiliary rear

bow 6, and the same pivotal means pivotally retains channel members 7 upon said auxiliary bow. The channel members 7 are of less length than the side arms of the auxiliary bows 6 and said members embrace the sides of said bows at the lower ends thereof. The upper ends of said channel members are provided with off-set pivots 8 for long members 9 that extend through or rest in guide rests or straps 10, carried by the inner sides of the front bow 1. The outer ends of the long members 9 are connected by rule joints 11 or other pivotal means to an over-hanging bow 12.

Pivotally connected to the inner sides of the long members 9, intermediate the ends thereof, is an auxiliary over-hanging bow 13 and all of said bows coöperate in supporting a canopy or cover 14. The bow 13 is provided with pins or shoulders 40 that engage the long members 9 and support the bow 13 at an inclination to said members.

In Fig. 2, the vehicle top is illustrated as collapsed or folded and when in such position the top is held by rests 15 carried by the sides of the vehicle. The bows practically fold into parallelism without injuring the canopy or cover, and the manner in which the bows are connected permits of one person quickly collapsing or setting up the vehicle top.

In Figs. 3 and 4 of the drawing there is illustrated a modification of the invention comprising a front bow 16 having the ends thereof pivotally connected in the ordinary and well known manner to irons or supports 17, carried by the sides of a vehicle 18, adjacent to the rear seat thereof. Pivotally connected to the front bow 16, contiguous to the irons 17, is a rear bow 19 and pivotally connected to said rear bow is an auxiliary rear bow 20, that can be folded against the rear bow 19 when the front and rear bows 16 and 19 are collapsed, as shown in Fig. 4. When the vehicle top is in a set-up position, the bows 16 and 19 are disposed at substantially a right angle to one another and the auxiliary rear bow 20 is in a plane substantially parallel to the front bow 16. Pivotally connected to the front bow 16, as at 21, are short members 22 having the outer ends thereof connected by rule joints 23 or other

2
 pivotal means to the ends of a bracing bow 24. The inner sides of the bracing bow 24 are provided with rest guides or straps 26 and extending through or resting in said 5 guides are long members 27, said members having the rear ends thereof pivotally connected, as at 28, to the front bow 16, above the pivotal connections 21 of the members 22. The forward ends of the long members 10 27 are connected by rule joints 29 or other pivotal means to an over-hanging bow 31, which, in a set-up position, is supported in substantially a horizontal plane. The over-hanging bow 31 has a rearwardly extending 15 auxiliary bow 32 provided with pins or shoulders 40 similar to the bow 13 and all of said bows are adapted to coöperate in supporting a canopy or hood 33 over the vehicle body. The forwardly extending 20 bows can be easily and quickly collapsed and compactly arranged relatively to the bows 16 and 19, as shown in Fig. 4, without cracking or injuring the cover or canopy. When collapsed, the ordinary rests 34 maintain the 25 folded top in the rear of the seat of the vehicle without obstructing the view or interfering with the comforts of the occupants of the vehicle. When the top is in a set-up position, the bracing bow 24 coöperates with the front bow 16 in correctly positioning the over-hanging bow 31, and it is 30 practically impossible for the forwardly extending bows to become accidentally displaced.
 35 In the preferred form of construction, the channel members 7 facilitate the folding or collapsing of the top and it is only necessary to break the rule joints 11 and swing the over-hanging bow 12 rearwardly. In performing this operation, the long members 9 shift in the guide rest 10 without interfering with the auxiliary rear bow 6, as the pivoted rear ends of the long members 9 can move forwardly through the medium of the channel members 7. It is these channel members 40 that allow the rule joints 11 to swing downwardly whereby the overhanging bow 12 can be easily swung rearwardly. If the rear ends of the long members 9 were pivotally connected to the rear auxiliary bow 6, then it would be practically impossible to raise the over-hanging bow 12 and control the same, besides the connection of the top or canopy 14 with the bow 13 would render 55 such movement practically impossible. It is therefore essential that the rear ends of the long member 9 be free to move independent of the rear auxiliary bow 6. It is also necessary that the rear ends of the long 60 members 9 be slightly curved, as shown in Fig. 1 to insure a proper folding, and after the top is given sufficient impetus it practically folds by gravity and thus permits of one person manipulating the same.
 65 All of the bows can be made of light and

durable tubing or other material and finished to harmonize with the body of the vehicle.

The preferred embodiments of my invention have been illustrated, but it is to be understood that the structural elements are susceptible to such variations and modifications as fall within the scope of the appended claims.

What I claim is:

1. A vehicle top comprising a front bow, a rear bow pivotally connected thereto, channel members pivotally connected to said front bow by the same pivotal means as said rear bow and engaging said rear bow, long members pivotally connected to outer ends of said channel members and movably supported by said front bow whereby pivoted ends of said long members can be moved toward said front bow independent of said rear bow, and an over-hanging bow pivotally connected to said long members. 75 80 85

2. A vehicle top comprising a front bow, an auxiliary rear bow pivotally connected to said front bow, channel members pivotally connected to said front bow and normally engaging said auxiliary rear bow, long members connected to said channel members and movably supported by said front bow, and an over-hanging bow supported by said long members. 90 95

3. A vehicle top comprising a front bow, guide rests carried thereby, long members extending through said guide rests, an auxiliary rear bow, an over-hanging bow supported by said long members, and movable means supported by said front bow connecting said long members and said front bow, whereby the rear ends of said long members can be moved toward said front bow independent of said auxiliary rear bow. 100 105

4. A vehicle top comprising a front bow, guide rests carried thereby, members movably supported by said guide rests, channel members pivotally connected to said front bow and connecting said members and said front bow, an over-hanging bow supported by said members, and means coöoperating with said front bow in supporting said channel members when said top is extended. 110 115

5. A vehicle top comprising a front bow, guide rests carried thereby, long members supported by said guide rests, channel members connecting said long members and said front bow, an over-hanging bow supported by said long members, an auxiliary overhanging bow supported by said long members, and means coöoperating with said front bow in supporting said channel members when said top is extended. 120 125

6. A vehicle top comprising a front bow, an auxiliary rear bow pivotally supported thereby, channel members pivotally connected to said front bow and normally resting upon said auxiliary rear bow, long members 130

connected to said channel members and
movably supported by said front bow, an
over-hanging bow, pivotally connected to
said long members, and an auxiliary over-
hanging bow pivotally connected to said
long members.

In testimony whereof I affix my signature
in presence of two witnesses.
